(57) **CLAIM**

I claim the ornamental design for a wall mount coat rack, as shown and described.

DESCRIPTION

FIG. 1 is a top, front, left side perspective view of a wall mount coat rack showing my new design;

FIG. 2 is a right side elevation view thereof;

FIG. 3 is a front elevation view thereof;

FIG. 4 is a left side elevation view thereof;

FIG. 5 is a bottom plan elevation view thereof;

FIG. 6 is a back elevation view thereof; and,

FIG. 7 is a top plan view thereof.

The broken lines shown in the drawings are included for the purpose of illustrating portions of the article that form no part of the claimed design.
